Primary Examiner — Lauren R Calve

CLAIM

The ornamental design for a capsule for mixing multiple substances, as shown and described.

DESCRIPTION

1. Capsule for mixing multiple substances

1.1 : Perspective

1.2 : Top

1.3 : Front

1.4 : Left

1.5 : Bottom

1.6 : Right

1.7 : Back

1.8 : Bottom perspective view

The broken lines shown represent portions of the capsule for
mixing multiple substances that form no part of the claimed
design.

1 Claim, 8 Drawing Sheets
